DIAPHRAGM PUMP

William C. Carter, Flint, Mich.

Original application February 23, 1928, Serial
No. 256,720. Divided and this application
February 18, 1933. Serial No. 657,357

1 Claim. (Cl. 103—150)

This application is a division of my pending application Serial No. 256,720, for Pump for liquid fuel supply systems, filed February 23, 1928.

One object of my present invention is to provide a diaphragm pump that is equipped with a novel means for controlling the position and flexing of the diaphragm, whereby the life of the diaphragm is prolonged, or thinner or lighter weight material may be used to form the diaphragm.

Another object is to provide a diaphragm pump that is equipped with a very thin fabric diaphragm and a novel means for maintaining the central portion of the diaphragm in correct position and also preventing said intermediate portion from bending or flopping unnecessarily when the direction of movement of the diaphragm is changed at the end of its stroke in either direction.

And still another object of my invention is to provide a diaphragm pump, in which a diaphragm, formed preferably of fabric, is combined with accurately guided reciprocating members that co-act with stationary members to effectively support or back up the intermediate flexible portion of the diaphragm at any and all points in the stroke of the diaphragm, and cause said intermediate portion to bend or flex in a circular line of gradually increasing diameter, or gradually decreasing diameter, according to the direction of stroke of the diaphragm.

Figure 1 of the drawing is a vertical sectional view of a diaphragm pump embodying my present invention.

Figure 2 is an enlarged fragmentary sectional view, illustrating the means that is used to control the bending or flexing of the intermediate portion of the diaphragm, showing the diaphragm at the end of its suction stroke; and

Figure 3 is a similar view, showing the diaphragm at the end of its discharge stroke.

In the accompanying drawing which illustrates the preferred form of my invention, G designates the diaphragm of the pump, which is preferably composed of either one or a plurality of layers of fabric treated with a substance that will render the fabric impervious to gasoline or water, without making it brittle or inflexible, said diaphragm G being arranged so that it forms one wall of a pumping chamber 1 into which liquid is drawn when said diaphragm flexes in one direction, and from which said liquid is forced when said diaphragm flexes in the opposite direction. The diaphragm G is disk-shaped and is herein illustrated as being arranged vertically at one side of a cav-

ity in the body portion H of the pump that constitutes the pumping chamber 1. The peripheral edge portion of said diaphragm is clamped between an annular part on the body portion H, and a co-operating member I that serves as a support for the body portion H and also as a housing for a mechanically-operated member K which forms part of the mechanism for flexing or actuating the diaphragm, G. Usually, the housing member I will be connected to and mounted on the outside of the crank case of an internal combustion engine, the crank case having an opening through which a portion of the mechanically operated member K projects into the crank case so as to co-operate with a cam or the like in the crank case, as shown in Figure 1.

It is immaterial, so far as my present invention is concerned, what type or kind of mechanism is used to actuate the diaphragm. The actuating mechanism herein illustrated comprises two compression springs 2 and 3 arranged on opposite sides of the diaphragm G. The spring 3, which is of greater force or strength than the spring 2, is used to impart a discharge stroke to the diaphragm so as to create pressure in the pumping chamber 1 and expel the liquid from said chamber, and the spring 2 is used to flex the diaphragm in the opposite direction, so as to create a suction in the chamber 1 and cause the liquid to be drawn into said chamber from a source of supply. Energy is stored up in the spring 3 by means of the rockable member K previously mentioned, which member K is herein illustrated as being provided with an arm 4 that co-operates with a cam or other rotatable actuating device 5 in the crank case, and also provided with an arm 6 that engages a cage or guide 9 which encases the spring 3. When the cam 5 is in rotation the element K rocks back and forth and exerts pressure on the spring cage 9 in such a way as to cause said cage to reciprocate, and thus alternately compress the spring 3 and permit said spring to expand. When the element K rocks in a direction to permit the spring 3 to expand, the pressure which said spring exerts on the diaphragm G imparts a discharge stroke to the diaphragm or moves said diaphragm to the left, looking at Figure 1, thus causing the spring 2 to be placed under compression. Thereafter, when the element K rocks in the opposite direction, said element compresses the spring 3, and during this period in the cycle of operations of the pump, the spring 2 expands and flexes the diaphragm to the right, thus causing the diaphragm to create a suction

in the chamber 1 of the pump. As is usual, the pump is provided with a spring-pressed inlet valve (not shown) that opens automatically and admits the liquid to the chamber 1 during the 5 suction stroke of the diaphragm G, and the pump is also provided with a discharge valve (not shown) that opens automatically and permits the liquid to escape from said pumping chamber during the discharge stroke of the dia- 10 phragm.

The diaphragm G is combined with the body portion H and with the housing member I in such a way as to produce a slight buckle in the diaphragm, which insures a quick movement or sudden 15 movement of the diaphragm each time it reverses or changes its direction of movement. In the pump herein illustrated the buckle in the diaphragm is produced by forcing the peripheral portion of the diaphragm into a circular recess, 20 of slightly less diameter than the diaphragm, formed in one of the parts between which the peripheral edge portion of the diaphragm is clamped. Thus, as shown in Figure 1, the portion of the supporting or housing member I that 25 is arranged in opposed relation to the annular part on the body portion H that bears against the peripheral portion of the diaphragm, is provided with a circular recess, designated by the reference character 21, of substantially the same 30 depth as the thickness of the diaphragm, but of slightly less diameter than the diaphragm. In assembling the diaphragm with the parts with which it co-operates, the peripheral edge portion of the diaphragm is forced into the recess 35 21 in the supporting member I, thus causing the diaphragm to buckle slightly, and thereafter, said supporting member is connected with the body portion H by means of screws or other suitable fastening devices 22 that pass through the said 40 supporting member I and through a flange 20 on the body portion H at a point beyond the peripheral edge of the diaphragm, as shown in Figure 1.

As previously stated, the peripheral portion of 45 the diaphragm G is clamped between opposed parts on the stationary members H and I. The central portion of the diaphragm is embraced by two reciprocating members J and J'. The stationary clamping members for the peripheral 50 portion of the diaphragm and the reciprocating members that embrace the central portion of the diaphragm, are so designed and proportioned that there is an intermediate portion of the dia- 55 phragm that is free to flex or bend back and forth when the pump is in operation, and thus provide for the reciprocating movement of the central portion of the diaphragm engaged by the members J and J', relatively to the stationary peripheral portion of the diaphragm clamped by 60 the members H and I. In order to maintain the central portion of the diaphragm G in concentric relationship with its peripheral portion and also prevent the flexible intermediate portion of the diaphragm from flexing or bending excessively, or from bending or flexing unnecessarily 65 and in such a manner that the fibres of same are liable to fatigue and break down, I construct the reciprocating members J and J' so that one or the other of said members will always be in direct 70 sliding engagement with a stationary portion or portions of the pump housing or casing, and I provide said members J and J' with a pair of reversely-curved surfaces that co-act with a pair of stationary reversely curved surfaces to 75 support or back up the flexible intermediate por-

tion of the diaphragm at any and all points in the stroke of the diaphragm. In the form of my invention herein illustrated the members J and J' are provided at their peripheral edges with flanges which are in sliding engagement but not in snug or fuel-tight contact with the body portion H and with the housing member I, respectively, as shown in Figure 1. Consequently, even though the diaphragm be formed of very thin fabric which has no inherent stiffness, the central reciprocating portion of the diaphragm will be maintained in concentric relationship with the stationary peripheral portion of the diaphragm, because the members J and J' are directly guided by the pump housing and one or the other of said members (preferably both members) will always be in sliding engagement with a stationary portion of the pump housing.

The pair of stationary, reversely curved surfaces previously mentioned, consist of convex surfaces 30 and 30^a carried by the housing members H and I, respectively, and the reversely curved surfaces with which they co-act, consist of convex surfaces 31 and 31^a on the reciprocating members J and J', respectively.

The curvature of the curved surfaces just referred to may be varied, but it is preferable to proportion or design said surfaces so that each surface has a drop equal to one-fourth of the stroke of the diaphragm and have the surfaces 31 and 31^a on the members J and J', respectively, located in such relationship with the surfaces 30 and 30^a on the members H and I, respectively, that substantially the entire area of the flexible intermediate portion of the diaphragm will be backed up and supported, and said intermediate portion effectively held against movement when the diaphragm is at the end of its stroke in either direction. When the diaphragm is at the end of its discharge stroke or pressure stroke, as shown in Figure 3, the movable, curved surface 31^a co-acts with the stationary curved surface 30 to hold the flexible intermediate portion of the diaphragm in such a way that when the stroke of the diaphragm is reversed, there is no liability of said intermediate portion flopping over and making an unnecessary bend, as would occur if no means were provided for holding the intermediate portion of the diaphragm against movement at this period in the cycle of operations of the pump. At the beginning of the suction stroke, i. e., when the members J and J' start to move to the right from the position shown in Figure 3, the suction that is created in the pumping chamber 1 is exerted on the intermediate portion of the diaphragm in such a manner that said intermediate portion is held against the stationary curved surface 30, thereby causing said intermediate portion to bend progressively in a circular line around the movable curved surface 31 when the member J reaches such a position that the curved surface 31 thereon contacts the intermediate portion of the diaphragm. As the member J continues to move to the right, the intermediate portion of the diaphragm will, in effect, be peeled off the stationary surface 30 and bent over the stationary surface 30^a; and when the end of the suction stroke is reached, the intermediate portion of the diaphragm will be clamped and held against movement, by the movable curved surface 31 and the co-acting stationary curved surface 30^a. At the reversal of the stroke, or when the members J and J' start to move to the left from the position shown in Figure 2, the pressure that is created in the pumping chamber 15

1 causes the intermediate portion of the diaphragm to remain in engagement with the stationary surface 30^a, and when the member J' reaches such a position that the curved surface 31^a thereon contacts the intermediate portion of the diaphragm, said intermediate portion will be bent over the surface 31^a, and the continued movement of the member J' to the left will cause the intermediate portion of the diaphragm to be peeled off the stationary surface 30^a and applied to the stationary surface 30, as shown in Figure 3, said curved surfaces 31^a and 30 co-acting with each other to prevent the intermediate portion of the diaphragm from flopping over at the reversal of the stroke of the diaphragm. In addition to performing the functions above described, the accurately guided reciprocating members J and J' cause the actuating force or pressure for the diaphragm to be centralized and applied substantially evenly to the diaphragm.

From the foregoing it will be understood that in my improved pump the central portion of the diaphragm is maintained in concentric relationship with the peripheral portion of the diaphragm, and the intermediate flexible portion of the diaphragm is effectively held and prevented from flopping over at the reverse of the stroke of the diaphragm, by the members J and J' and the

stationary portions of the pump housing with which they co-act. Moreover, the intermediate portion of the diaphragm is caused to flex or bend on a circular line of gradually increasing or diminishing radius in such a way that the fibres of the diaphragm are not subjected to abrupt bends or injurious strains. Consequently, the life of the diaphragm is materially prolonged and thinner or lighter weight material can be safely used in the construction of the diaphragm.

Having thus described my invention, what I claim as new and desire to secure by Letters Patent is:

A fuel pump provided with a housing structure, a non-metallic, flexible diaphragm arranged so as to form one wall of a pumping chamber, into and out of which fuel is drawn and discharged by the movement of the diaphragm, clamping members on the housing structure that embrace the peripheral portion of the diaphragm, reciprocating members engaging the central portion of the diaphragm and arranged in direct sliding contact with the housing structure, and reversely-curved surfaces on said housing structure and on said reciprocating members, located at opposite sides of the diaphragm, for the purpose described.
